UNITED STATES PATENT OFFICE.

JOHN F. HUGHES, OF PENNS GROVE, NEW JERSEY.

DRYING APPARATUS.

Application filed October 12, 1920. Serial No. 416,357.

To all whom it may concern:

Be it known that I, JOHN F. HUGHES, a citizen of the United States, residing at Penns Grove, in the county of Salem and 5 State of New Jersey, have invented certain new and useful Improvements in Drying Apparatus, of which the following is a specification.

One object of my invention is to provide 10 improved means which will facilitate and expedite the drying of coloring material, dyes or the like, such for example as used in the mixing of paint. This material, which before being dried is in a plastic condition, 15 has been found, prior to my present invention, exceptionally difficult to dry and usually is dried in shallow trays which is expensive and slow and the removal of the dried material from the trays is a tedious, 20 slow and expensive operation.

With the use of my improved apparatus, the material can be dried directly in barrels and the dried material can be permitted if desired to remain in the barrel until 25 needed for use.

Another object is to so arrange the parts of my improved apparatus that material in a number of barrels can be simultaneously dried and that the drying action will be 30 uniform so that all parts of the material will be properly and thoroughly dried to suit ideal conditions.

These objects, and other advantageous ends which will be described hereinafter, I 35 attain in the following manner, reference being had to the accompanying drawings in which—

Figure 1 is an enlarged fragmentary elevation, partly in section, showing one full 40 unit of my improved drying apparatus in position to effect the drying of the material,

Figure 2 is a view of the same general character as shown in Figure 1 showing how a drying element can be either inserted 45 in or removed from a container, such as a barrel, containing the material,

Figure 3 is a fragmentary sectional elevation showing the conducting means for the heating fluid and also illustrating the 50 construction whereby the above mentioned heating element can be moved upwardly and downwardly with respect to the container,

Figure 4 is an enlarged fragmentary sectional perspective view taken through a por-

tion of the above mentioned heating element,

Figure 5 is an elevation showing a stationary stripping or cleaning blade arranged relatively to a screen frame which may be mounted in the barrel; the screen 60 being omitted, and

Figures 6 and 7 are respectively diagrammatic top plan view and side elevation illustrating how a number of units of my improved apparatus can be controlled to effect the drying of the material within a number of the containers.

Referring to the drawings, 8 represents a vacuum or suction room or chamber which when in use has a vacuum established therein; said room having a pipe 9 leading from its top, as shown in Figures 1 and 2, to permit suction of the air from the chamber and the floor 10 of the room, as shown in detail in Figures 1 and 2, is made hollow 70 so as to have a heating fluid 11, such as hot water, passed therethrough to heat the interior of the chamber. The floor 10 at various positions has holes 12 therein into which closely fit turntables 13, each capable 75 of supporting a barrel 14 or other suitable container as clearly shown in Figures 1 and 2. These barrels are arranged in rows as clearly shown in Figure 6 and directly above the barrels are supported inlet manifold 80 pipes 15 which communicate with a main inlet conduit 16 for a heating fluid, such as for example as hot water.

Another series of outlet manifold pipes 17 are positioned respectively above the 90 rows of barrels and communicate with a main header 18; said header 18 leading to the interior of the floor 10, as shown at 19, to supply the floor with hot water, after which the hot water after passing through 95 the floor will run out of an outlet pipe 20 as shown in Figures 6 and 7. The water leads from the manifolds 15 through drying means hereinafter described, prior to passing into the outlet manifolds 17.

Over each of the turntables 13 is mounted a supporting structure which is illustrated in the form of a hanger 21 which supports a collar 22 which is secured to an externally screw threaded pipe 23; said pipe depending toward the turntable and fitting within the internal screw threads of another pipe 24. This pipe 24 has a spider

25 secured thereto; said spider having a hand-wheel 26 secured thereto, as clearly shown in Figures 1 and 2. A hollow drying element 27, which consists of a tube of 5 substantially flattened tapered cross section as shown in Figure 4, is made in the form of a double helix which surrounds the pipe 24 and at its upper end is secured to the spider 25. In other words, the element 27 includes 10 two communicating spirally wound portions 28 and 29 which are connected with each other at their top and which serve as conduits for the heating fluid in a manner now to be described.

15 The upper end of the pipe 23, as clearly shown in Figure 4, communicates with a fitting 30 which is connected with the outlet manifolds 17 by means of pipes 31. The lower end of the spirally wound portion 29 20 of the heating element 27 is connected to a fitting 32 which communicates with the interior of the pipe 24. Two tubes 33 and 34 are positioned within the pipes 23 and 24 and are in screw threaded engagement with 25 each other as shown in Figure 3; the lower end of the tube 34 being in communication with the bottom of the spiral portion 28 by means of a coupling nipple 35 located within the fitting 32. The upper end of the 30 tube 33 is connected through the medium of a pipe 36 with the inlet manifold 15 and it is thus obvious that the heating fluid from the inlet manifold 15 will pass downwardly through the tubes 33 and 34 then upwardly 35 through the spiral portion 28, then downwardly through the spiral portion 29 into the pipe 24, then upwardly through the pipes 24 and 23 and through the pipe 31 to the manifold 17. In this manner all of the 40 heating units will receive the heat from the heating fluid after which the heating fluid will pass through the floor 10 and out through the outlet pipe 20. Each of the barrels 37 has a frame 38 mounted therein; 45 said frame including a screen 39. A stripper 40 depends within the screen frame and is made substantially yoke or U-shaped, the upper ends of which are adapted to be attached to braces 41 which are pivotally 50 mounted on posts 42. The braces 41 are arranged in a series and have their opposite ends turned upwardly and secured to the spiders 25, as clearly shown in Figure 1. Thus the strippers 40 are held against 55 rotation. The material to be dried is placed within the screen frames 38 and the barrels are rolled upon the turntables 13; the braces 41 being turned on their pivots, as shown in Figure 2, to permit this operation; it 60 being noted that the spiral members 27 can be moved into an upper position above the barrels by turning the hand-wheels 26 so that the pipes 24 will ride up on the pipes 23. To insert the drying elements 27 into 65 the material, the hand-wheels are turned in

an opposite direction and the heating elements will descend into the material within the screen frames 38. The pivoted braces can then be swung into the position shown in Figure 1 and secured by clamping screws 70 43 and the top ends of the strippers 40 can be secured to the under portions of the braces 41 by screws 44. The turntables 13 are then rotated by any suitable mechanism preferably at a slow speed and the spiral 75 heating element will tend to slightly agitate the material and due to the absorption of heat therefrom, the material will be thoroughly dried.

The mesh of the screens 39 is preferably 80 made sufficiently fine to keep the material, which as previously stated is originally in a plastic state, within the confines of the screen frames during the drying operation so that the moisture of the material will be 85 liberated at the outer surface of the frames and pass into the barrel, I also preferably employ auxiliary vacuum pipes 45, as shown in Figure 1, for establishing additional 90 vacuum within the barrels between the frames 38 and the inner surfaces of the barrels so as to expedite the drying operation.

It will be noted that the heating fluid circulates through the spirally wound portions 95 of the heating elements 27 and the rotation of the material relatively to the spirally wound portions of the heating element will bring new portions of the material constantly adjacent the heating element so that the 100 heat may be absorbed thereby and the material will be kept in a condition to permit the ready escape of the moisture and since the apparatus is confined within a chamber in which a vacuum or suction is established, the 105 moisture will be quickly removed and the material will be thoroughly and uniformly dried.

To remove the heating elements 27 from the dried material which is in powdered form, it is merely necessary to rotate the hand-wheels 26 after the braces 41 have been 110 released and swung into the position shown in Figure 2. It will be noted that after the heating element is removed the barrel with the dried material and the screen therein can be removed from its position on the turntable and by raising the screen out of the barrel, the dried material will remain 115 in the barrel and can be used when needed. The screen after preferably being cleaned by the strippers 40 of the frame can be replaced in another barrel and the operation repeated. I am thus enabled to dry material 120 within a number of containers and in this manner the drying of such material as above set forth is facilitated and can be accomplished at a low cost and at comparatively 125 great speed.

By arranging the heating elements 27 in 130

spiral form they will easily cut their way into the material without greatly disturbing the mass when the elements are initially inserted and by making the spiral portions of 5 a construction including a wide surface area they will readily permit the absorption of heat therefrom by the material to cause the evaporation of moisture. While I have described but one unit in detail it will be understood that any number of units can be 10 utilized for example as is shown diagrammatically in Figures 5 and 6.

While I have described my invention as taking a particular form, it will be understood 15 that the various parts of my invention may be changed without departing from the spirit thereof, and hence I do not limit myself to the precise construction set forth, but consider that I am at liberty to 20 make such changes and alterations as fairly come within the scope of the appended claims.

Having thus described my invention, what I claim as new and desire to secure by 25 Letters Patent is:—

1. Apparatus of the character described including a screened member for containing the material to be dried; and heating means adapted to be inserted into the material 30 within the screened member; substantially as described.

2. Apparatus of the character described including a screened member for containing the material to be dried; heating means adapted to be inserted into the material 35 within the screened member; and means for effecting relative rotation between the screened member and the heating means; substantially as described.

3. Apparatus of the character described including a screened member for containing the material to be dried; heating means adapted to be inserted into the material 40 within the screened member; means for moving said screened member; and scraping means adapted to scrape the material from the inner surface of the screened member; substantially as described.

4. Apparatus of the character described 50 including a screened member for containing the material to be dried, and heating means adapted to be inserted into the material within the screened member, the heating unit including a spirally wound conduit for a heating fluid.

5. Apparatus for drying material of the character described including a container; a screen frame adapted to hold the material; a heating element adapted to be projected 60 into the material within the frame; and means for rotating said frame relatively to the heating unit, said heating unit includ-

ing a spirally wound portion; substantially as described.

6. Apparatus for drying material of the character described including a cylindrical screen frame adapted to hold the material; and a heating element adapted to be projected into the material within the frame; substantially as described. 65

7. Apparatus for drying material of the character described including a floor having a hole therein; a turntable in register with said hole; a container for said material to be dried supported on said turntable; and a heating unit adapted to be projected into 70 said material; substantially as described.

8. Apparatus for drying material of the character described including a floor having a hole therein; a turntable in register with said hole; a container for said material to be dried supported on said turntable; a heating unit adapted to be projected into said material, said floor being a part of a chamber; and means for heating said floor; substantially 80 as described.

9. Apparatus for drying material of the character described including a floor having a hole therein; a turntable in register with said hole; a container for said material to be dried supported on said turntable; a heating unit adapted to be projected into said material, said floor being a part of a chamber; means for heating said floor; and means 90 for establishing vacuum in said chamber; substantially as described.

10. Apparatus for drying material of the character described including a floor; a turntable located adjacent the floor; a container for material to be dried positioned on said turntable, a screened frame in said container; a stripper within said frame; means for preventing relative rotation between said stripper and frame; and a heating unit adapted to be inserted within said screened 100 frame; substantially as described.

11. Apparatus of the character described including a screened member for containing the material to be dried; heating means adapted to be inserted into the material 110 within the screened member; means for effecting relative rotation between the screened member and the heating means; and means for establishing suction at a position immediately adjacent said screened member; substantially as described. 115

In testimony whereof I have signed my name to this specification in the presence of two subscribing witnesses.

JOHN F. HUGHES.
